UNITED STATES PATENT OFFICE.

PAUL FREDERIK DEGN, OF BREMEN, GERMANY.

FLYING APPARATUS.

No. 922,756.

Specification of Letters Patent.

Patented May 25, 1909.

Application filed October 6, 1908. Serial No. 456,484.

To all whom it may concern:

Be it known that I, PAUL FREDERIK DEGN, graduated engineer, and a subject of the German Emperor, residing at 3 Wilhadistrasse, 5 in the city of Bremen, in the German Empire, have invented a certain new and useful Flying Apparatus, of which the following is a specification.

In those kinds of flying apparatus the supporting faces of which consist of air screws with vertical shafts, and where there is a component of motion, working horizontally in relation to the surrounding air, those wings which at any moment are advancing in 10 the direction of flight, possess a velocity, increased by the amount of the horizontal movement, while the velocity of the wings, the movement of which is opposed to the direction of flight, with respect to the air, is reduced by the same amount, as would result 15 from the speed of revolution of the screws or propellers. This fact produces the effect that the upward pressure of those wings which reciprocate in the direction of flight, is much greater, than the upward pressure of 20 the wings, moving inversely. When the wings of the air propellers are made of thin material which acquires its tension only by the action of centrifugal force, the wings 25 form an undulating, fluttering movement in consequence of the difference of upward pressures, and produce considerable bending strains in the axis of rotation.

The invention hereinafter described, is intended, to dispense with this difference of 30 upward pressures of the wings of a propeller and with the injurious actions resulting therefrom. With this end in view the forward or entering edge of the wings is connected to the shaft by means of a longer lever, than the rear or "leaving" edge. The 35 connection of the last mentioned edge with the shaft is effected preferably by means of as small a lever arm, as possible, for instance 40 by a sleeve, mounted upon the axis of rotation. Thus, when by the action of the increased upward pressure, the wing which operates in the direction of flight is raised, the angle of ascension of the same is reduced, so 45 that the increase of upward pressure of the wing is considerably less, than would result 50 from the velocity of the wing relatively to the air, when the ratio of ascension is not changed. When the wing which moves in 55 the opposite direction, is lowered, the angle of ascension of the wing is increased, and the

upward pressure is therefore reduced only little accordingly. This manner of securing the wings, results in an additional advantage, in case the driving motor should refuse 60 to work during the flight from any reason whatever.

The connection between the motor or the motors and the propellers may be constructed in such a manner, by means of a ratchet 65 and pawl connection for instance, that the propellers are automatically uncoupled from the motor, when the motor stops, or the number of revolutions of the same is reduced below a certain definite limit, the propellers 70 retaining thereby their rotation by means of the energy of movement which they still possess. However, the velocity of rotation of the propellers is soon decreased, and consequently the tension of the wings also. 75 This results in the raising of the wings in relation to the flying apparatus which commences to descend, the "leaving" or rear edge of the wings being raised quicker than the entering edge, so that after some time 80 the leaving or rear edge is higher than the entering edge. The resistance of the air of the descending flying apparatus which acts from below, now continues to rotate the propellers in the same direction, as was previously effected by the motor. After some time, the state of equilibrium is attained; the speed of rotation of the propellers decreasing no more. Hence, the wings retain 85 their tension by means of centrifugal force, 90 and the flying apparatus drops down to the ground from any height desired, and with but moderate velocity. The state of equilibrium is attained at a velocity which is the more high, the more the resistances are diminished which the wings have to overcome 95 in their movement. The most noticeable resistance is the front resistance of the preceding wing edge. In order to reduce this resistance to the lowest amount, and furthermore, in order to prevent the turning over of the wing edges, the latter are provided 100 with suitable braces.

By securing the entering edges of the wings to a wheel, which presents a number of constructional advantages, the rear or "leaving" edge strikes against the rim of the wheel, when the motor refuses to work, so that the said edge cannot be raised higher at this point, than the entering edge. In order 110 however, to cause the propellers to assume the inverse inclination upon the stopping of

the motor, so that they are kept rotating by the resistance of the air, the weights of the wings are distributed in such a manner, that the tension of the air entering edge becomes 5 larger than that of the air leaving edge. The somewhat lower tension of the leaving edge presents the additional advantage, that the angle of ascension of the wing is decreased from the axis of rotation toward the 10 outer edge which is very favorable for the efficiency, that is to say for the ratio of available upward pressure to the amount of work produced.

The sleeves to which the air leaving edges 15 of the wings are secured, are displaceably arranged upon the shaft. By a displacement of the said sleeves, the degree of ascension of the propellers is increased or diminished, and consequently the force, necessary for the rotation 20 of the propellers also. When the forces, required for the rotation of the two propellers, working in opposite directions, are equal, the gondola which is rigidly connected to the motor, does not perform any 25 rotating movement. In case however, the rotating resistance of one of the propellers is larger, the gondola is turned in the opposite direction. The sleeves may be displaced from the gondola, by means of wire ropes for 30 instance, and in such a manner, that the sleeve of one of the propellers is lowered, while that of the other propeller is raised. Thus, the operator is entirely at liberty, to turn or oscillate the gondola at will, or to 35 ride straight ahead, and to effect complete steering, without the use of a steering rudder.

On the accompanying drawings:—Figure 1 shows a vertical section through a flying apparatus, according to my invention, the 40 apparatus being shown to fly toward the onlooker; Figs. 2 to 4 illustrate different forms of construction of the air propellers; Fig. 5 shows the inclination of the outer edges of the wings; Fig. 6 is a top view of the 45 gondola; Fig. 7 illustrates the ratchet-pawl coupling between the motor and the propellers.

As will be seen from Fig. 1, the tubular concentric shafts 1 and 2 are provided with 50 wheels 3 which are preferably constructed in the manner of cycle wheels. To these wheels the air entering edges 4 of the wings are connected, while the air leaving edges 5 of the wings are connected to the sleeves 6 and 7 by means of the cords 8. As follows from Fig. 1 by the lifting of one wing, the angle of ascension of the same, is immediately decreased. The left wing of the upper propeller, and the right hand wing of the lower 60 propeller move in the direction of flight, so as to be somewhat raised, in consequence thereof the angle of ascension has become smaller than that of the two other wings.

The broken lines indicate the position of the 65 wings, when the apparatus drops to the

ground upon the refusing to work of the motor. The two motors 9 operate the two shafts in opposite directions by means of four bevel wheels 10. Between the motors and the bevel wheels ratchet pawl couplings 70 11 are inserted in such a manner (Fig. 7), as to enable the propellers to continue their rotation in the same direction, when the motor should happen to run too slowly or stops suddenly. To the yoke 12 which contains the journals for the shafts and for the pivots of the bevel wheels, the motors and the gondola 13 are rigidly secured. The sleeves 6 and 7 may be displaced from the platform of the gondola by means of the pitman rod 14, the yoke 15, the cord 16, and the guide rollers 17. Thus, when the operator who is posted upon the gondola, and between the two parallel ends of the cord, moves the cord for instance in the direction 80 of the right hand arrow I (Fig. 6), the sleeve 6 is moved downward, while the sleeve 7 is moved upward, the gondola being rotated in the direction of the arrow II.

In the form of construction of the air propellers, in accordance with Fig. 2, the wings are braced by means of thin triangular pieces 18 of metal for the purpose of reducing the front resistance, and of preventing the turning over of the edges of the wings, while 90 the tension of the air entering edge of the wing increases by making the outer ends of the wings from a trapezoidal piece of sheet metal 19, the broader side of which presents the preceding edge. Instead of the triangular pieces of sheet metal 18, needles 20 may also be used for the bracing of the wing edges (Fig. 3).

By this means the effect is produced, that the bending strains, occurring upon the starting of the air propellers, or caused by the action of the wind, when the apparatus stops, in consequence of the fluttering of the wings, are distributed more uniformly upon the entire wing edge, while in the form of construction according to Fig. 105 2 these strains are chiefly transmitted upon the points between the pieces of sheet metal, thereby causing danger to the wings by rapid wear, after being used for some time.

As also appears from Fig. 3, the air leaving, 110 and the air entering edges of each two adjoining wings 21 may be connected by a rope or by a chain 22. But it is also possible of course, to employ several ropes or chains instead of one. When the air propeller is 115 now turned, the ropes or chains 22 are projected outward by the action of centrifugal force, so as to be put under tension. By this means however, they effect a pull in the direction of the periphery upon the wings 21, 120 so that the wings are put under tension and made taut, so as to prevent the injurious fluttering of the same.

By securing the rope or the chain in a suitable manner, it becomes also possible, to 130

impart any desired degree of ascension to the propeller in this manner. A device of this kind is shown in Fig. 4 in section. As appears from this figure, the ropes or chains 5 are arranged in this case not in the plane of the wing, but they are connected to the wings 21 by means of lever arms. During the rotation the ropes or chains will not only put tension on the wings 21, but at the same 10 time, they will impart to them the degree of ascension resulting from the blade angle shown in the figure, and the amount of which will of course be dependent upon said lever arm.

15 What I claim, and desire to secure my Letters Patent of the United States is:—

1. In a flying apparatus, a rotatable shaft, a yielding wing, first means for connecting the air entering edge of the wing to the shaft, 20 and second means for connecting the air leaving edge of said wing to the shaft, the first means having a greater leverage than the second means.

2. In a flying apparatus, a pair of concentric shafts, means for rotating said shafts in opposite directions, a set of yielding wings 25 for each of said shafts, means for connecting the air entering edge of each wing to its shaft, and means for connecting the air leaving edge of each wing to its shaft, the first-named means having a greater leverage than the second-named means.

3. In a flying apparatus, a rotatable shaft, a wheel and a sleeve mounted thereon, the 30 wheel being of greater diameter than the sleeve, a wing, means for connecting the air entering edge of said wing to the wheel, and means for connecting the air leaving edge of said wing to the sleeve.

4. In a flying apparatus, a rotatable shaft, 40 a set of yielding wings, first means for connecting the air entering edges of said wings to said shaft, second means for connecting the air leaving edges of said wings to said shaft, the first means having a greater leverage than 45 the second means, and means for connecting the air entering edge of one wing with the air leaving edge of the adjoining wing.

5. In a flying apparatus, a rotatable shaft, 50 a yielding wing having an outer sheet metal rim, first means for connecting the air entering edge of the wing to the shaft, and second means for connecting the air leaving edge of said wing to the shaft, the first means having a greater leverage than the second means.

6. In a flying apparatus, a rotatable shaft, a yielding wing having a reinforced air entering edge and a reinforced air leaving edge, 55 first means for connecting the air entering edge of the wing to the shaft, and second means for connecting the air leaving edge of said wing to the shaft, the first means having a greater leverage than the second means.

7. In a flying apparatus, a motor, a shaft, 60 a pawl and ratchet coupling between motor and shaft, a yielding wing, first means for connecting the air entering edge of the wing to the shaft, and second means for connecting the air leaving edge of said wing to the shaft, the first means having a greater leverage 70 than the second means.

Signed by me at Bremen, Germany, this 23rd day of September 1908.

PAUL FREDERIK DEGN.
